UNITED STATES PATENT OFFICE.

CHARLES W. COHN, OF NEW YORK, N. Y.

DESIGN FOR A SHOW-CASE.

45,371.

Specification for Design.

Patented Mar. 10, 1914.

Application filed November 21, 1913. Serial No. 802,319. Term of patent 7 years.

To all whom it may concern:

Be it known that I, CHARLES W. COHN, a citizen of the United States of America, residing in the borough of Manhattan, city, county, and State of New York, have invented a new, original, and ornamental Design for Show-Cases, of which the following is a specification, reference being had to the accompanying drawing, forming part thereof.

I claim—

The ornamental design for a show case as shown.

In witness whereof, I have hereunto signed my name in the presence of two subscribing witnesses.

CHARLES W. COHN.
